(57) **CLAIM**

The ornamental design for a gift packaging in the form of a castle, as shown and described.

DESCRIPTION

FIG. 1 is a perspective view of a gift packaging in the form of a castle showing my new design;

FIG. 2 is a front side elevation view thereof;

FIG. 3 is a back side elevation view thereof;

FIG. 4 is a left side elevation view thereof;

FIG. 5 is a right side elevation view thereof; and,

FIG. 6 is a top plan view thereof.

The broken lines are shown for the purpose of illustrating parts of the article that form no part of the claim.

1 Claim, 6 Drawing Sheets
